UNITED STATES PATENT OFFICE.

WALTER J. COATE, OF MAYWOOD, ILLINOIS, ASSIGNOR TO AMERICAN CAN COMPANY, OF NEW YORK, N. Y., A CORPORATION OF NEW JERSEY.

DISPLAY-RACK.

1,246,883.

Specification of Letters Patent. Patented Nov. 20, 1917.

Application filed December 1, 1913. Serial No. 803,876.

To all whom it may concern:

Be it known that I, WALTER J. COATE, a citizen of the United States, residing in Maywood, in the county of Cook and State 5 of Illinois, have invented a new and useful Improvement in Display-Racks, of which the following is a specification.

This invention relates to improvements in display racks and more particularly to improvements in display racks for holding a 10 number of cracker cans.

An object of the invention is to provide a sheet metal display rack, relatively cheap in construction, of pleasing design, adapted to 15 hold a plurality of boxes, having means whereby any particular can may be drawn out and held in such a position that the cover thereof may be lifted, and to provide a display rack employing a minimum amount 20 of sheet metal.

The invention furthermore consists in the improvements in the parts and devices and in the novel combinations of the parts and devices herein shown, described or claimed.

25 In the drawing forming a part of this specification, Figure 1 is a front elevation of a rack embodying my improvements and showing in dotted lines two cracker cans in position. Fig. 2 is an end elevation of the 30 structure illustrated in Fig. 1. Fig. 3 is a vertical sectional view, upon an enlarged scale, taken substantially on the line 3—3 of Fig. 1 and showing in dotted lines a cracker can pulled out and in position to 35 have its cover lifted. Figs. 4 and 5 are horizontal sectional views taken substantially on the lines 4—4 and 5—5, respectively, of Fig. 3, and Fig. 6 is a detail plan view of one of the slidable can supporting 40 and holding plates.

In the drawing, the rack is shown as composed of a frame A having a plurality of combined supporting and holding plates or members B slidably and tiltably mounted 45 in the frame. The frame A comprises a pair of vertical end walls 10, 10 made of sheet metal provided with inwardly turned flanges 11, see Fig. 4. The end walls 10 are mounted on and supported by a horizontal 50 board 12 which in turn is held raised from the floor by a plurality of blocks 13. The tops of the end walls 10 are connected by a horizontally extending top wall 14 formed of sheet metal and having upwardly extending 55 back and front flanges 15 and 16, re-

spectively, the latter being rounded at the corners and wide enough to be decorated with advertising matter, printing or lithographing, as will be understood. A pair of diagonally arranged bars 17 are placed on 60 the rear of the frame to brace the parts. Extending longitudinally of the frame and fixed with respect thereto and arranged in three sets or tiers, are a plurality of rods 18, 19 and 20, each set or tier having two rods 65 18 on the same level, a rod 19 in front thereof and disposed therebelow, and a rod 20, the latter being located above the rods 18. The rods 18 form a supporting shelf for a plurality of slidably and tiltably mounted 70 members B, each of the latter comprising a sheet metal plate 21 having downwardly extended side flanges 22, the latter being doubled back upon themselves at their lower edges, as shown at 23, to thereby form 75 a more substantial bearing on the rods 18 over which the members B are slidable back and forth. The said flanges 22 are provided with slots 24 through which the rods 20 are inserted, thereby providing a pin and 80 slot connection between each of the members B and the frame A and thus preventing accidental removal of any of the members B. The top plate 21 of each member B has stamped up therefrom a plurality of 85 sets of tangs 25, said sets being arranged to correspond with the four sides of a square cracker can 26 and, as will be understood, the tangs 25 are more or less resilient and serve to clamp the can when inserted in 90 place therebetween. A plurality of transversely extending sheet metal division plates 27 are employed which are mounted on the rods 18, 19 and 20, one between each pair of members B. At the bottom of the 95 frame the slidable members B are omitted and in place thereof a horizontally extending sheet metal plate 28 is employed on top of the board 12 and an angle 29 is secured thereto to properly position the cans as the 100 same are slid back in place on the plate 28. Each of the rods 18, 19 and 20 extends from end to end of the frame and the same are held in place by nuts 30 threaded to the ends thereof. Each member B, on its front side, 105 is provided with a depending finger piece 31 in the form of a flange integral with the plate 21 and by which the member B can be more readily manipulated.

As will be understood, the cans are placed 110

on the members B and held in position thereon by the tangs 25. The members B are independently movable and slidable back and forth on the rods 18, 18 and as the 5 same are drawn outwardly from the frame the weight thereof will cause them to tilt downwardly as indicated by dotted lines in Figs. 2 and 3 and they will come to rest on the rods 19, the pin and slot connections (20 10 and 24), preventing the members B from falling out. With the cans in the tilted position, shown in dotted lines, it is apparent that the covers thereof may be lifted up and the desired amounts of the cans' contents removed after which the covers may be closed and the cans put back in their normal 15 position.

As shown in the drawing, the display rack is adapted to hold three cans in each tier 20 but this number may be varied as desired. It will furthermore be obvious that the display rack may be adapted for holding cracker cans or other cans of different widths than the ones shown on the drawing 25 without changing the overall dimensions of the frame. This is done by removing the rods 20, after which the members B can be removed and others of different width substituted therefor and held in place by re- 30 placing the rods 20. In this way I provide simple and convenient means adapting the rack for holding different size cans.

Although I have herein shown and described what I now consider the preferred 35 embodiment of my improvement, yet it will be understood that various changes and modifications may be made without departing from the spirit of the invention, and all such changes and modifications are contemplated as come within the scope of the claims 40 appended hereto.

I claim:

1. A display rack comprising in combination: vertical end frame members; a series 45 of shelves arranged at different heights between and connected with said end members and comprising transverse removable rods; and a series of slidable and tilting members each adapted to support a box or can and 50 mounted on said rods and slidably and pivotally connected with the fixed part of the said rack and limited in sliding and tilting by certain of said rods.

2. A display rack comprising in combination: vertical end frame members; a series 55 of shelves arranged at different heights between and connected with said end members and comprising transverse removable shelf rods; and a series of slidable members each 60 adapted to support a box or can and mounted on said shelf rods and slidably connected with the fixed part of the said rack, and a series of division plates through which the 65 said rods pass, for separating the said slidable members, the said division plates being

adapted to be changed in position and number according to the number of slidable members.

3. A display rack comprising, in combination: vertical end frame members; a plurality of rods extending horizontally through said frame and forming a vertical series of shelves; slidable members mounted on said rods and adapted to carry cans; through pivot rods for said slidable members which 70 limit their movement and on which they are adapted to tilt; and front supporting rods which arrest said members in tilted position when the latter have been drawn forward.

4. A display rack comprising in combination: a frame having transverse shelf rods; a can-holding slide resting on said shelf rods; a transverse guide rod engaging said slide and limiting its sliding movement; and a transverse front supporting rod limiting 85 the downward tilting of said slide when drawn forward.

5. A display rack comprising, in combination: a fixed rack portion having shelves the front parts of which are at a distance to the 90 rear of the front of the rack; slidable members mounted on said shelves and movable forward thereon; pivotal connections between said members and the fixed rack portion; and transverse rods below the level of 95 the shelves for holding said members in forward and tilted position.

6. A can-supporting and display rack comprising in combination: vertical end frame members; a series of transverse shelf rods 100 one above another attached to the said frame members; a series of guide rods attached to the frame members forward of the shelf rods; a series of supporting rods forward of said guide rods; and can-carrying slides 105 movable on said shelf rods, engaging said guide rods, and forwardly and downwardly tilttable to rest on said supporting rods.

7. In a display rack of the character described, a slidable combined cracker-can supporting and holding member comprising a sheet of metal having down-turned side flanges, the latter having their lower edges doubled back upon themselves, said sheet having a plurality of tangs struck up therefrom, said tangs being arranged to engage the sides of the can, substantially as specified.

8. A display rack comprising, in combination: a frame having a plurality of rods extending longitudinally thereof, some of said rods being arranged in the same horizontal plane and one of them being located in front of and below said horizontally arranged rods; and a can supporting and holding member slidable on the rods arranged in the same horizontal plane and adapted to be supported in part in a tilted position by the rod located below said horizontal plane, substantially as specified.

9. A display rack comprising, in combination: a frame having a plurality of longitudinally extending rods 18, 19 and 20, the rods 18 being located in the same horizontal 5 plane and the rods 19 and 20 below and above said plane, respectively; and member B slidably mounted on said rods 18 and slotted to receive the rod 20 and adapted to be

supported in an inclined position on the rod 19, substantially as specified. 10

Signed this 26th day of November, 1913,
in the presence of two witnesses.

WALTER J. COATE.
